UNITED STATES PATENT OFFICE.

JOHN C. HAYES, JR., OF CHICAGO, ILLINOIS, ASSIGNOR TO FREYN ENGINEERING COMPANY, OF CHICAGO, ILLINOIS, A CORPORATION OF MAINE.

AIR DISTRIBUTION TO FURNACES.

Application filed March 6, 1926. Serial No. 92,773.

The present invention relates to air distribution to furnaces.

The present invention will be described with particular reference to the distribution 5 of air to a blast furnace. Great care and expense are involved in blast furnace practice in getting proper distribution of the ore, coke and stone in the furnace stack for the purpose of securing a uniform resistance to the upward flow of air and the products of combustion. Many schemes have been used, with the view to bringing about a proper stock distribution.

In spite of the expedients above referred 15 to, a serious problem exists in blast furnace practice in securing a uniform air distribution. The present invention contemplates a structure for automatically maintaining a fixed and predetermined flow of air to each 20 of the tuyères of a blast furnace. According to the present invention, not only does the tuyère furthest away from the bustle pipe connection to the hot blast main have the same flow of air as the one closest to the connection, 25 but the result is also attained that the part of the furnace opposite any tuyère which may at any moment offer a greater resistance to the flow of air will be supplied its proper quota under a greater pressure.

An object of the present invention is to provide 30 a structure having the advantages immediately above referred to.

A further object is to provide control means 35 for the air supply of a blast furnace which is applicable to blast furnace construction as now known and used and which will be reliable in operation.

A further object is to provide control means 40 for the air supply of a blast furnace which will automatically maintain constant the ratio of the volume of air delivered by each tuyère compared to the total volume of air delivered to said furnace regardless of conditions within the furnace.

A further object is to provide control means 45 for the air supply of a blast furnace which are adapted to provide variations in the ratio above referred to.

A further object is to provide an improved 50 method of blast furnace operation.

Further objects will appear as the description proceeds.

Referring to the drawings—

Figure 1 is a top plan view, partly in sec-

tion, illustrating a blast furnace having a 55 bustle pipe for delivering air thereto; and

Figure 2 is a diagrammatic view illustrating the principles of the present invention.

The numeral 10 indicates the wall of a blast furnace, which blast furnace is provided with 60 the tuyères 11—11. In the illustrated embodiment of the present invention, ten tuyères are illustrated. The bustle pipe 12 is provided for supplying air to the various tuyères. For the purpose of connecting the bustle pipe 65 12 with the various tuyères, a number of pipes 13—13 are provided, each leading to one of the tuyères 11. Each pipe 13 is provided with a valve 14 for controlling the resistance to the flow of air through the corresponding pipe 70 13. According to the present invention, said valves 14 are automatically controlled by means which are indicated diagrammatically in Figure 2.

Referring to Figure 2, a plurality of control members 15—15 are indicated. One of the control members 15 is provided for each of the pipes 13. For the purpose of this specification the connections of only one of the control members 15 need be described, it being 75 understood that the connections of the other control members 15—15 to their corresponding pipes 13 and their corresponding valves 14 are substantially the same.

Each of the control members 15 is connected 80 to be responsive to the flow of air through the corresponding pipe 13, which flow is proportional to the difference in pressure at two points in said corresponding pipe 13. Said points are indicated in the drawings by the 85 numerals 16 and 17. Said control members involve certain relay mechanism, which controls cables 18, one cable 18 being connected to each valve 14. Control members responsive to differential pressures in a pipe line 90 are well known in the art and may be readily purchased in the open market which control members make use of Pitot tubes, orifice plates, Venturi tubes and the like. Therefore 95 a more detailed description of the control mechanism is unnecessary in this specification. It will be understood, of course, that the present invention is not limited to the differential pressure means for controlling the valves 14—14, it being within the scope of 100 the present invention to use any preferred means responsive to the flow of air through the individual pipes 13—13 to control said 105

valves 14—14. It is preferred to have means whereby the settings of the various control means may be adjusted. The drawing illustrates diagrammatically one form of adjusting means which may be used, it being understood that any other preferred adjusting means may be used if desired. The illustrated adjusting means includes an adjustable weight 18^a which may be disposed at different selectable distances from the fulcrum point of the lever 18^b which controls the cable 18. The numeral 18^c indicates a relay or movement multiplying means which may be interposed between each lever 18^b and its corresponding cable 18. Relays or movement multiplying means suitable for the purpose are readily purchasable in the open market and need not be described in detail herein.

By way of example, it may be assumed that the furnace illustrated is being supplied with a substantially constant number of cubic feet of air per minute. Normally, the throttling valve 14 above each of the tuyères will be partly closed, so that there is a slight excess of pressure in the bustle pipe over that required to pass said substantially constant number of cubic feet per minute to the furnace. In a perfectly working furnace, all of the throttling valves 14 will be at certain mid positions, and the positions would probably be at greater closure for the tuyères closest to the bustle pipe connection to the hot blast main and in more open positions for the ones furthest away. These may be considered the normal positions of the valves. If it be assumed that one section of the furnace in front of a certain tuyère begins to offer a greater resistance to the flow of air than the others, the control member 15 corresponding to said tuyère will immediately open the corresponding throttle valve 14, taking advantage of the excess pressure in the bustle pipe. Consequently a greater pressure of air will be applied to that tuyère which had been

opposed by the greater resistance. Preferably the control arrangement would be such that the total flow of air to the furnace would be substantially constant. By reason of the present invention, operators, instead of using considerably less than the maximum hot blast temperatures for fear of getting into furnace troubles brought about by faulty air distribution, faulty stock distribution, or faulty furnace lines, will use the higher hot blast temperatures, whereby the efficiency and capacity of the furnace will be very greatly increased.

Though a preferred embodiment of the present invention has been described in detail, many modifications will occur to those skilled in the art. It is intended to cover all such modifications that fall within the scope of the appended claims.

What is claimed is—

1. A blast furnace having a plurality of tuyères, a bustle pipe, pipe lines leading from said bustle pipe to said tuyères, each of said pipe lines being provided with a valve and independent control means for said valves, each of said means being responsive to the flow of air through its corresponding pipe line for controlling its corresponding valve to maintain substantially constant the volume of air delivered through its corresponding pipe line.

2. The method of operating a blast furnace which comprises delivering a substantially constant flow of air thereto under pressure in excess of that normally required at the tuyères, distributing said air at uniformly spaced regions around said blast furnace, throttling said air to said various regions, and varying the extent of said throttling in accordance with the volume of air delivered to said various regions.

Signed at Chicago, Illinois, this 27 day of February, 1926.

JOHN C. HAYES, JR.
